(57) **CLAIM**

The ornamental design for a hand wearable sensor mount, as shown and described.

DESCRIPTION

FIG. 1 is a front perspective view of a hand wearable sensor mount;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top elevation view thereof;

FIG. 7 is a bottom elevation view thereof;

FIG. 8 is a rear perspective view thereof; and,

FIG. 9 is an environmental view thereof.

The broken lines shown in the drawings are only provided to illustrate the environment of the design, and form no part of the claimed design.
